UNITED STATES PATENT OFFICE.

ROBERT BOYLE, OF DETROIT, MICHIGAN

IMPROVEMENT IN TEMPERATURE-ALARMS.

Specification forming part of Letters Patent No. 39,794, dated September 8, 1863.

To all whom it may concern:

Be it known that I, ROBERT BOYLE, of Detroit, in the county of Wayne and State of Michigan, have invented a new and Improved Temperature-Alarm; and I do hereby declare that the following is a full, clear, and exact description of the same, reference being had to the accompanying drawings, making a part of this specification, in which—

Figure 1 represents an elevation of my device with the necessary connections in working order. Fig. 2 is a plan or top view of the same.

Similar letters of reference in both views indicate corresponding parts.

The invention consists in the arrangement of an oscillating index operated upon by a float projecting from a tube partially filled with mercury or other suitable liquid, and operating between a gate or two stops that are adjustable upon a graduated arc, in combination with an electro-magnetic hammer operating upon a suitable alarm-bell in such a manner that when the temperature in the room or space where the apparatus is put up rises above or sinks below a certain point the oscillating index, by the expansion or contraction of the mercury in the tube and consequent rising or falling of the float, is brought in contact with either of the stops on the graduated arc, and thereby the circuit of the electro-magnetic alarm is closed and the hammer is caused to sound the alarm-bell.

To enable others skilled in the art to make and use my invention, I will proceed to describe its construction and operation with reference to the drawings.

A represents a board or frame, provided with a loop, a, so that it can be conveniently suspended from the walls of a house, or it may be arranged in any other desirable manner, so that it can be put up in the place where the instrument is to be used. Secured on the surface of this frame or board is a tube, B, of glass or any other suitable material, which is partially filled with mercury or other suitable liquid, and from which a float, C, projects that acts upon the oscillating index D.

The tube B may be provided with a bulb, b, of a much larger diameter than that of the tube, so that a slight change in the temperature causes a considerable rise and fall of the mercury in the tube, and consequently of the

float C. This float consists of a cylindrical piece of wood or other suitable material, and its top end may be provided with a notch to receive the index, which is made of a piece of copper wire or other good conductor of electricity, and which is fulcrated on a pin or stud, e, that rises from the frame A. Said index moves over an arc, E, which is made of sheet-brass or other good conductor of electricity, which projects above the surface of the frame A; and which supports the index D, so that the same does not come in contact with the graduated metal arc E. The point of the index D is confined between a gate, G, which is adjustable on the metal arc E, by means of a clasp, d, and which extends over or straddles thirty (more or less) degrees of the scale on the graduated arc. Instead of the gate G, however, two separate stops may be used, each of which can be adjusted on the graduated arc, so that the number of degrees situated between them can be varied at pleasure.

H represents the electro-magnetic alarm, which consists of the hammer e, alarm-bell f, helix h, armature i, key k, and anvil l. The armature swings on a pivot fastened in the platform which supports the whole device, and the hammer e is connected to said armature by a stem, e'. The key k extends from the armature over the anvil l, and its front end is secured in a small plate, k', of ivory or other non-conductor of electricity, so that an electric contact between the key and the anvil is prevented. A spiral spring, m, attached to the key k draws the armature back from the core of the helix h, and the bell f is so situated that the hammer e strikes it wherever the armature is attracted by the core of the helix.

The connections of the several parts of my instrument with each other and with the battery and the operation are as follows:

The stud e connects by a wire, 10, with one—say the positive—pole of the battery, and the negative pole of the battery connects by a wire, 11, with one end of the helix. The other end, 13, of the helix is fastened to the plate k' in such a manner that when said plate is down upon the anvil the end of the helix is in metallic contact with the anvil or with a portion of the anvil. A wire, 12, leading from the graduated arc E to the anvil l, completes the connection. The gate G is adjusted on the arc E so that the point of the index cannot rise

above nor sink down below certain points on said arc without coming in contact with a portion of the gate. If the temperature of the atmosphere surrounding the tube B now rises high enough to bring the point of the index in contact with the upper part of the gate, or if the temperature sinks so low that the point of the index touches the lower part of the gate, the current is closed, passing from the battery through the wire 10, stud c, index D, gate G, arc E, wire 12, anvil l, wire 13, helix h, and through wire 11 back to the battery. The armature is attracted and the hammer strikes the bell. As soon as the armature is attracted the metallic contact between the wire 13 and the anvil is interrupted and the current is broken, the armature, with the hammer e, recedes, the current is again closed, the hammer strikes again, and the alarm is sounded as long as the index D remains in contact with the gate.

This invention is applicable as a fire-alarm in private buildings, in warehouses, in factories, or on board of vessels, and it is particularly useful as temperature-alarm in green-houses or other places where it is desirable to maintain a uniform temperature. If used in a green-house, the frame A, with tube B and index D, is put up in the interior of the house, and the alarm is placed in the room of the attendant, the connections being made substantially in the manner previously described.

The gate G is set so as to permit the index to oscillate between the desired limits. If by some accident the temperature rises above or falls below a certain point, the alarm is sounded, and the attendant can remedy the evil before any damage has been done. The same remark applies to drying-houses, chemical laboratories, and many other places where it is desirable to maintain a uniform temperature, and where it is equally objectionable if the temperature sinks below as it is if it rises above a certain point.

When used as a fire-alarm the gate G must be so arranged that the electric current is closed only when the temperature, and with it the index, rises to a certain point, and consequently the alarm is only sounded when that point is reached, but it must not be sounded when the temperature sinks.

I do not claim, broadly, the employment of an electro-magnetic apparatus in connection with a temperature-alarm; but,

Having thus fully described my invention, what I claim as new, and desire to secure by Letters Patent, is—

The combination of the gate G, graduated arc E, and electric alarm H with the index D, float C, and mercury-tube B, in the manner herein shown and described.

ROBERT BOYLE.
